AWNNG

Harvey L. Bartholomew, Kansas City, Mo.

Application November 6, 1957, Serial No. 694,760

3 Claims. (Cl. 160—58)

This invention relates to awnings, and more particularly to fabric awnings having edges that fit closely against the window casing.

Conventional fabric awnings are usually formed of heavy canvas treated with fireproofing material which adds to the stiffness of the canvas. Such awnings also are usually arranged whereby the edges adjacent the window casing fit closely thereagainst with the result that air is normally trapped in the upper portion of the awning and sun shining on the awning causes the trapped air to increase in temperature. Also, strong currents of air or winds tend to raise the awning and then when the wind is reduced in velocity the awnings drop down, providing a severe jar on the canvas parts, and in many instances, damaging the hardware. The stiffness of the canvas makes it difficult to raise same as the canvas resists folding thereby increasing the wear on the canvas, ropes and hardware for the awning.

The principal objects of the present invention are to provide an awning with ventilating openings which allow strong currents of air to find egress from under the awning; to provide such an awning wherein the ventilating openings allow additional light to enter thereunder whereby the rooms having the windows covered by the awnings are lighter; to provide such an awning wherein the ventilating opening is positioned to facilitate the folding of the canvas when the awning is raised thereby reducing the effort for raising and lowering operations and giving longer life to the ropes and hardware fitting for the awnings; to provide an awning structure with a ventilating opening structure that is reinforced at the opening to aid in holding the fabric outstretched and to prevent tearing or damage to the awning; and to provide a ventilated awning structure that is economical to manufacture and affording passage of light and air under the awning and increased life to the awning and mountings thereof.

In accomplishing these and other objects of the present invention, I have provided improved details of structure, the preferred form of which is illustrated in the accompanying drawings, wherein:

Fig. 1 is a perspective view of an awning embodying the present invention positioned over a window casing.

Fig. 2 is a vertical sectional view through the awning taken on the line 2—2, Fig. 1.

Fig. 3 is a vertical section through the awning taken on the line 3—3, Fig. 1.

Fig. 4 is a perspective view of the awning in partially raised folded position.

Referring more in detail to the drawings:

1 designates a canvas awning having a top or front wall 2, and side walls or members 3 of substantially triangular form. The top or front wall 2 slopes downwardly and outwardly from the upper edge 4 thereof which is suitably secured to a window casing 5 in any conventional manner. In the illustrated structure, the upper portion of the top or front wall 2 is folded back under said top wall and sewed by a line of stitching 6 forming a loop 7 through which extends the head rod

2

8 secured to the window casing 5 by suitable fastening devices as in conventional structures.

Depending from the lower end of the front wall 2 are valances 9, and behind the valance at the lower end 5 of the inclined front wall 2 is a strip of fabric 10 sewed by lines of stitching 11 and 12 to said front wall and valance to form the usual horizontal pocket 13 in which is mounted a rod 14 of a frame 15 that is substantially U-shaped. The frame 15 has legs 16 extending from 10 the ends of the bar 14 under and engaging the side panels or members 3 and preferably through horizontal pockets 13 thereon. The legs 16 terminate in fittings 17 pivotally mounted as at 18 on suitable brackets 19 secured to the window casing 5.

15 The side panels preferably have lower edges 20 substantially on a level with the lower edges of the valances 9 when the awning is in lowered position. The vertical edges 21 of said side panels preferably substantially engage the face of the window casing 5 whereby the top 20 and sides of the awning fit closely against said window casing. The side panels 3 preferably have their upper edges turned outwardly to form flanges 22 engaging the underside of the top or front panel 2, with the side marginal portions 23 of the top wall turned under to underlie 25 the flange 22 and sewed thereto by lines of stitching 24 forming a triple thickness of the fabric or canvas at the side edges of the top or front wall of the awning.

The side panels or walls 3 have ventilating openings 25 formed in the upper portions thereof. In the illustrated 30 structure, the ventilating openings 25 are substantially triangular in shape with edge portions 26 turned inwardly in underlapping relation and sewed to the side panels 3 by lines of stitching 27 to form hem-like edges for the 35 openings 25 and provide at least a double thickness of fabric or canvas around said opening 25. The upper edge 28 and vertical or rear edge 29 of the opening 25 are spaced from the edges of the side panels as illustrated in Fig. 3. With this arrangement, when the awning is in lowered position, the awning protects the associated window 40 from the hot rays of the sun but at the same time enables additional light to enter under the awning affording more light into the room behind the window. The openings 25 also enable air to pass through and circulate under the awning, permitting passage of heated air 45 from under the awning and thereby reducing the temperature of the air under the awning. The openings also permit egress of currents of air from under the awning eliminating tendency of strong currents to lift the awning and resulting shocks to the awning and hardware that 50 will result from winds or strong air currents.

As in conventional practice, the awning has ropes 30 secured to the bar 14 and extending upwardly through suitable members 31 adjacent the head rod 8 and then downwardly along the side where the end of the rope 55 is adapted to be connected to a fastening member 32. When it is desired to raise the awning, the rope is disengaged from the fastening member 32 and pulled, swinging the frame 15 upwardly as illustrated in Fig. 4. The openings 25 reduce the stiffness at the upper portion of 60 the awning whereby the side panels are easily folded and the top wall folds, reducing the pull on the rope that is necessary to raise the awning. This also tends to reduce the tendency of the awning walls to buckle at the connections of the front and side walls and the stress resulting therefrom during the raising operation, thereby 65 providing longer life for the fabric of the awning.

It is to be understood that while I have illustrated and described one form of my invention, it is not to be limited to the specific form or arrangement of parts herein described and shown except insofar as such limitations 70 are included in the claims.

What I claim and desire to secure by Letters Patent is;

1. An awning for use on a window frame, said awning having a fabric sloping top wall and fabric side walls depending therefrom adjacent longitudinal side edges of the sloping top wall, said side walls being triangular, said sloping top wall having an upper portion for connection to the upper portion of a window frame, a frame connected to said awning walls and having connection to the window frame, a line of stitching uniting the forward edge of the side walls and the top wall side margins, said side walls each having an unobstructed light and ventilating opening adjacent the top portion thereof and disposed in spaced relation from the edges of said side walls, the entire marginal portion of the side walls adjacent the light and ventilating openings being turned inwardly in overlying relation to said side walls to form a double thickness therearound, and lines of stitching uniting the inturned marginal portions to the side walls.

2. An awning for use on a window frame, said awning having a fabric sloping top wall and fabric side walls depending therefrom adjacent longitudinal side edges of the sloping top wall, said side walls being triangular and each including a vertically disposed rear edge, a sloping front edge and a lower edge meeting said front edge at an acute angle, said sloping top wall having an upper portion for connection to the upper portion of a window frame, a frame connected to said awning walls and having connection to the window frame, out-turned flanges on the forward edges of the side walls engaging the underside of the top sloping wall of the awning with the outer edges of said flanges spaced from the side edges of the sloping top wall, inturned side flanges on the sloping top wall turned inwardly under the side wall flanges whereby said side wall flanges are embraced by the top wall margins and side flanges, a line of stitching uniting the side wall flanges and the top wall side margins and flanges, each said side wall having an unobstructed triangular light and ventilating opening adjacent the top portion thereof and defined by front lower and rear edges disposed in spaced substantially parallel relation to the respective edges of the respective side wall, the entire marginal portion of the side walls adjacent the light and ventilating openings being turned inwardly in overlying relation to said side walls to form a double thickness therearound, and lines of stitching uniting the inturned marginal portions to the side walls.

3. An awning for use on a window frame, said awning having a fabric sloping top wall and fabric side walls depending therefrom adjacent longitudinal side edges of the sloping top wall, said side walls being triangular and each including a sloping front edge and a lower edge meeting the front edge at an acute angle and a substantially vertically disposed rear edge, said sloping top wall having an upper portion for connection to the upper portion of a window frame, a U-shaped frame connected to the sloping top wall and side walls of the awning and having ends for pivotal connection to the window frame for raising and lowering said awning, said U-shaped frame holding the sloping top wall and side walls in straight extended position when the awning is in lowered position, 15 out-turned flanges on the sloping front edges of the side walls engaging the underside of the top sloping wall of the awning with the outer edges of said flanges spaced from the side edges of the sloping top wall, inturned side flanges on the sloping top wall turned inwardly under the 20 side wall flanges whereby said side wall flanges are embraced by the top wall margins and side flanges, a line of stitching uniting the side wall flanges and the top wall side margins and flanges, each said side wall having an unobstructed triangular light and ventilating opening adjacent the top portion thereof and defined by front lower and rear edges disposed in spaced substantially parallel relation to the respective edges of the respective side walls, the entire marginal portion of the side wall adjacent the light and ventilating openings being 25 turned inwardly in overlying relation to said side walls to form a double thickness completely therearound, said double thickness of the side walls at the front and rear of the light and ventilating openings extending substantially to the top wall and rear edges of the side walls respectively, and lines of stitching uniting the inturned marginal portions to the side walls.
